(57) **CLAIM**

The ornamental design for a kitchen media player dock with clock radio, as shown and described.

DESCRIPTION

FIG. 1 is a front, perspective view in a first, open condition of a kitchen media player dock with clock radio showing my new design;

FIG. 2 is a front view thereof;

FIG. 3 is a rear view thereof;

FIG. 4 is a top view thereof;

FIG. 5 is a bottom view thereof;

FIG. 6 is a side view thereof, the opposite side view being a mirror image;

FIG. 7 is a front, perspective view thereof in a second, closed condition;

FIG. 8 is a front view thereof;

FIG. 9 is a rear view thereof;

FIG. 10 is a top view thereof;

FIG. 11 is a bottom view thereof;

FIG. 12 is a side view thereof, the opposite side view being a mirror image; and,

FIG. 13 is a partial, cross sectional view thereof at the arrows 13—13 in FIG. 8.

The broken lines in the drawings illustrate environmental material that forms no part of the claimed design.
